(57) **CLAIM**

The ornamental design for an alarm system, as shown and described.

DESCRIPTION

FIG. 1 is a perspective view of an alarm system showing my new design;

FIG. 2 is a back perspective view thereof;

FIG. 3 is a front elevation view of the alarm system showing the switch, the alarm and the sensor shown separate for ease of illustration.

FIG. 4 is back view thereof;

FIG. 5 is left side view thereof;

FIG. 6 is a right side view thereof;

FIG. 7 is a top plan view of the alarm system showing the switch, the alarm and the sensor in an alternate orientation with the elements separated for ease of illustration; and,

FIG. 8 is a bottom view thereof.

The broken lines in the drawings illustrate portions of the alarm system that forms no part of the claimed design.
